UNITED STATES PATENT OFFICE.

ELMER FRANKLIN PHELPS, OF IDAHO SPRINGS, COLORADO.

AUTOMATIC FEED-WATER-VALVE-OPERATING DEVICE.

1,317,940.

Specification of Letters Patent.

Patented Oct. 7, 1919.

Application filed October 21, 1918. Serial No. 259,157.

To all whom it may concern:

Be it known that I, ELMER F. PHELPS, a citizen of the United States, residing at Idaho Springs, in the county of Clear Creek 5 and State of Colorado, have invented a new and useful Automatic Feed-Water-Valve-Operating Device, of which the following is a specification.

The present invention appertains to an 10 apparatus applicable to boilers and operable for controlling the valve of the feed water pipe, whereby the lowering of the water level in the boiler results in the automatic opening of the feed water valve to 15 bring the water up to the normal level in which event said valve is automatically closed, it being the object of the invention to provide a novel and improved apparatus of that character.

20 One of the objects of the invention is the provision of a feed water valve controlling mechanism which will not operate to open the valve until the water level has lowered a predetermined amount, in which event the 25 valve is opened and will remain open for a sufficient length of time until the water level is brought up to normal in which event the mechanism is operable for quickly shutting off the flow of water into the boiler.

30 Another object of the invention is the provision of an apparatus of the nature indicated embodying steam or pressure fluid actuated means for controlling the feed water valve and float controlled means for 35 controlling the supply of steam or pressure fluid to said valve actuating means.

It is also within the scope of the invention to provide an automatic feed water valve operating device which is comparatively simple, compact and inexpensive in construction, as well as being thoroughly practical, reliable and efficient in use.

With the foregoing and other objects in view which will appear as the description 45 proceeds, the invention resides in the combination and arrangement of parts and in the details of construction hereinafter described and claimed, it being understood that changes in the precise embodiment of 50 the invention herein disclosed can be made within the scope of what is claimed without departing from the spirit of the invention.

The invention is illustrated in the accompanying drawing, wherein the figure is a 55 vertical section of the mechanism, portions being illustrated in elevation.

In carrying out the invention, there is provided an upright cylindrical casing 1 forming a float chamber therein, and having attached to the upper and lower ends 60 thereof, the heads or castings 2 and 3, respectively. The upper head 2 has a passage 4 for connection with the boiler adjacent or slightly above the normal water level so that steam flows through the passage 4 into 65 the upper portion of the float chamber, while the lower head 3 has a passage 5 to communicate with the boiler below the normal water level so that water flows through the passage 5 into the lower portion 70 of the float chamber. The water level within the float chamber will thus be the same as that in the boiler, the steam and water pressure within the float chamber being equalized.

75 Disposed within the float chamber is a suitable float 6, preferably of cylindrical contour, and having its lower end reduced or tapered to provide an annular shoulder 7. The float 6 has a central depending stem 80 8 provided at its lower end with a conical or needle valve 9, and the lower head 3 is provided with a bore 10 intersecting the passage or channel 5 and tapered to provide a valve seat 11 for the valve 9, whereby 85 when the float 6 drops, the valve 9 will stand across the passage 5 to close the same, thereby shutting off the flow of water through the passage 5 into the lower portion 90 of the float chamber.

A drain cock 12 is attached to the head 3 at the lower end of the bore 10, said cock being normally closed, and when opened enables the water and sediment to be drained from the float chamber for purpose of 95 cleaning.

The float 6 is provided with a centrally arranged upwardly projecting stem 13, preferably in alignment with the stem 8, and working snugly within a vertical bore 14 100 with which the upper head 2 is provided, said bore 14 intersecting the passage or channel 17 with which the head 2 is provided. The end of the bore 14 is tapered, as at 16, to provide a valve seat for the valve 15 of the 105 stem 13, said valve 15 being tapered to seat within the seat 16 across the passage or channel 17 for closing said passage.

One end of the passage 17 is connected in any suitable manner with the boiler above 110 the normal water level so that dry steam is supplied to the passage 17, and the other end

of said passage communicates with the upper end of a cylinder or tubular member 18 having its ends engaged to the heads 2 and 3. The tubular member 18 is disposed in a vertical position and has its upper end communicating with the passage 17. A piston 19 is slideable snugly within the tubular member 18 and is provided with a downwardly projecting stem 20 sliding snugly through the lower head 3. A coiled wire expansion spring 21 is disposed between the lower head 3 and the piston 19 for normally raising said piston. The lower protruding end of the stem 20 has an eye 22 which is adapted for connection with the ordinary gate valve which controls the feed water injector of the boiler to supply the water thereto, said piston 19 being normally raised to close the gate valve. When the piston 19 is depressed against the tension of the spring 21, the downward movement of the stem 20 is arranged to open the gate valve.

The upper head 2 is provided with a passage or duct 23 extending from the passage 17 to the atmosphere, said passage 23 communicating with the passage 17 between the valve 15 and its seat and the cylinder 18, and the said passage 23 intersecting the bore 14. The stem 13 is provided with an aperture 24 normally registering or alining with the passage 23, whereby the upper end of the tubular member 18 is in communication with the atmosphere, to allow the steam or pressure fluid to escape, so that the piston 19 can be elevated under the influence of the spring 21 for normally closing the feed water valve, the float 6 being normally raised so that the valve 15 is seated to close the passage 17.

A trip device employed for normally holding the float 6 raised even though the water level lowers slightly, said trip device being float controlled and releasing the main float 6 after the water level has lowered a predetermined amount. Said trip device embodies an angular or bell crank lever 25 having its elbow pivoted to the lower end of a hanger 26 attached to the upper head 2 at one side of the float 6, a roller 27 being pivoted to the free end of one arm of said lever 25 and normally bearing against the shoulder 7 to thereby support the float 6, said shoulder 7 seating upon the roller 27 so that the float 6 cannot drop until the lever 25 is swung to move the roller 27 out of the path of the float 6. The other arm of the lever 25 is pivoted to the upper end of an upwardly projecting central stem 28 of a trip or secondary float 29 disposed within the float chamber adjacent the bottom thereof. The float 29 has a downwardly projecting guide stem 30 working in a bore 31 drilled in the lower head 3, to guide the float 29 for vertical movement.

In operation, supposing the apparatus is to be properly installed upon the boiler,

when the water level in the boiler is normal, the water in filling the float chamber will raise the float 6 to seat the valve 15 and unseat the valve 9, the valve stem 13 being brought to position so that its aperture 24 registers with the passage 23. The float 29 is also raised to swing the lever 25 so that the roller 27 is moved under the shoulder 7 to hold the float 6 raised. The steam cannot flow into the tubular member or cylinder 18, since the valve 15 is closed, but said tubular member is connected with the atmosphere to allow the steam or pressure fluid to escape, whereby the piston 19 is raised for closing the gate valve. The steam can flow into the upper portion of the float chamber by way of the passage 4, and the water can flow into and out of the lower portion of the float chamber by way of the passage 5 which is now opened due to the elevation of the valve 9. Consequently, when the water level in the boiler lowers, the water level in the float chamber will be lowered correspondingly, but even though the water level in the float chamber be lowered below the float 6, said float cannot drop, since it is held in raised position by the trip lever 25. Said trip lever will be held in active position as long as there is sufficient water within the float chamber to hold the auxiliary float 29 raised, but as soon as the water level lowers a predetermined amount, whereby the float 29 is lowered, the lever 25 will be swung away from the float 6, thereby allowing said float 6 to drop quickly. The roller 27 will now bear against one side of the float 6, and not until the float 6 is again elevated can the lever 25 swing to the position illustrated in the drawing for again holding the float 6 in raised position. The valve 9 in being seated due to the lowering of the float 6 will close the passage 5, and the upper valve 15 being unseated will open the passage 17 to allow the steam to flow into the tubular member 18 above the piston 19, the passage 23 being closed since the aperture 24 is moved downwardly out of registration therewith. This prevents the escape of steam through the passage 23 from the passage 17. The steam will force the piston 19 downwardly, to open the gate valve, whereby the water will be forced into the boiler to compensate for the water lost by evaporation or otherwise. The parts will remain in the position just indicated, until the normal water level in the boiler is restored, in which event the water will rush into the float chamber by way of the passage 4, so as to quickly fill the float chamber. The float 6 will therefore be raised quickly to seat the valve 15 and unseat the valve 9, and as soon as the float 6 is raised completely, the float 29 will be raised to swing the lever 25 to position for holding the float 6 in place. The valve 15 being seated will shut off the supply 130

ply of steam to the tubular member 18, whereby the piston 19 will again be raised for closing the gate valve.

The present mechanism is comparatively simple and inexpensive, can be readily installed upon various boilers and operates in a comparatively simple and practical manner.

Having thus described the invention, what is claimed as new is:—

1. In a device of the character described, a float chamber having upper and lower heads provided with passages communicating with the upper and lower ends of the float chamber, a cylinder engaged between said heads, the upper head having a pressure fluid passage communicating with the upper end of said cylinder, a piston working in said cylinder and having a stem extending through one head for operating a feed water controlling valve, a float within said chamber, and a valve operated by said float and controlling the last mentioned passage.

2. In a device of the character described, a float chamber having upper and lower heads, an upright cylinder engaged between said heads, a piston working in said cylinder and having a downwardly projecting stem working through the lower head, a coiled wire expansion spring between the lower head and piston, the upper head having a passage communicating with the upper end of the cylinder, a valve controlling said passage, and a float within the float chamber operating said valve.

3. In a device of the character described, a float chamber having an upper head provided with a pressure fluid passage and a bore intersecting said passage and having a tapered valve seat, pressure fluid operated means communicating with said passage for controlling a feed water controlling valve, said head having a duct extending from the atmosphere to said passage between said valve seat and means and intersecting said bore, and a float within said chamber having a stem working within said bore and provided with a tapered valve normally seated within said seat to close said passage, the valve stem having an aperture normally registering with said duct.

4. In a device of the character described, a float chamber having upper and lower heads provided with passages communicat-

ing with the upper and lower ends of said chamber and adapted to communicate with a boiler, a cylinder engaged between said heads, a spring pressed piston within said cylinder for operating a feed water controlling valve, the upper head having a pressure fluid passage communicating with the upper end of said cylinder, a float within said chamber having an upwardly projecting stem provided with a valve controlling the last mentioned passage, said float having a downwardly projecting stem provided with a valve controlling the passage of the lower head, and a float controlled trip within said chamber coöperable with said float for holding it until the water level lowers a predetermined amount within said chamber.

5. In a device of the character described, a float chamber having upper and lower heads having passages communicating with the upper and lower ends of said chamber and adapted to communicate with a boiler, a cylinder between said heads, a spring pressed piston within said cylinder for operating a feed water controlling valve, the upper head having a pressure fluid passage communicating with the upper end of said cylinder, the upper head having a bore intersecting said pressure fluid passage, the lower head having a bore intersecting its passage, a main float within said chamber having upwardly and downwardly projecting stems working in the respective bores, the upper upwardly projecting stem having a valve for normally closing the pressure fluid passage, the downwardly projecting stem having a valve for closing the passage of the lower head when said float is lowered, a trip lever pivoted within said chamber and engageable with said float for holding it raised, and a lower auxiliary float connected to said lever for releasing it when the auxiliary float is lowered and for swinging the lever into engagement with the first mentioned float when the auxiliary float is raised.

In testimony that I claim the foregoing as my own I have hereto affixed my signature in the presence of two witnesses.
